ELECTRICAL CUT-OUT.

1,287,451.

Specification of Letters Patent. Patented Dec. 10, 1918.

Application filed May 25, 1918. Serial No. 286,558.

To all whom it may concern:

Be it known that I, JOSEPH SACHS, a citizen of the United States, residing at Hartford, in the county of Hartford and State 5 of Connecticut, have invented a new and useful Improvement in Electrical Cut-Outs, of which the following is a specification.

Electrical cut-out bases have previously been constructed so that they fulfill only 10 their designed purposes and no other, that is, there have been single line, two line and multiple line bases, designed for use respectively in one, two or more main line circuits, and there have been single line, two line and 15 multiple line bases designed for use respectively in one, two or more branch line circuits. These have been constructed so that they are useful only under the particular conditions for which they are adapted. 20 Therefore in order to be prepared to meet all of the various requirements of electrical installations a manufacturer must make, a dealer or contractor must carry in stock and an installer or wire-man must take to the 25 job an excess number of all of the several varieties of main line and branch line bases that might be needed for completing the work. This is costly for the contractor and adds labor to the installer. Furthermore, it 30 frequently happens that the stock is incomplete and the particular cut-out that is wanted is not at hand and cannot be obtained when needed.

The object of this invention is to eliminate 35 the necessity of manufacturing, keeping in stock and carrying to the place of installation a large number of each of many varieties of cut-outs. This object is attained by constructing one wire units so that they 40 are capable of use singly or can be joined together to form two wire or multiple wire units for either main line or branch line circuits, and providing tap units for connection to or between the single or combined branch 45 line cut-outs and the circuit wires, and thus enable every practical condition or emergency arising in an installation to be met with a minimum variety of units.

Figure 1 of the accompanying drawings 50 shows a plan of a number of individual single wire units and tap units joined together to form multiple wire branch bases, connected with three main line wires. Fig. 2 shows an edge view of the branch and tap 55 units connected as illustrated in Fig. 1.

Fig. 3 shows a plan of one of the single wire units. Fig. 4 shows a plan of a single wire unit of modified construction. Fig. 5 shows a plan and Fig. 6 an edge view of one of the tap units. Fig. 7 shows a plan and Fig. 8 an edge view of another tap unit having a tap strap in the middle wire channel. Fig. 9 shows a plan and Fig. 10 an edge view of a modified form of tap unit.

With an adequate number of these single 55 wire line and tap units practically every condition arising in the wiring of all main and branch circuits of any installation may be met.

The line units illustrated are of the in- 70 closed fuse cut-out type and each consists of an oblong base 1 of porcelain or other insulating material provided on its upper face with two pair of metallic spring clips 2 for receiving an inclosed fuse 3 of the cartridge 75 variety. In the sides of these bases are vertically extending dove-tail grooves 4. These bases may be used as single line bases in either main line or branch circuits. When it is necessary to make up a two line or multiple line base, either for a main circuit or branch circuit, two or more, according to the circumstances, of these single line bases are placed side by side and wedges 5 of wood or other material are driven into the adjacent 80 dove-tail grooves in the sides of the bases, as shown in Fig. 1. Instead of forming the dove-tail grooves in both sides of the base, as shown in Fig. 3, dove-tail grooves may be formed in one side and dove-tail tenons 6 85 may be formed on the other side, as shown in Fig. 4, and when bases made in this manner are put together the tenons are inserted into the adjacent grooves, uniting the parts into a single structure. In this manner any number 90 of these individual line bases may be connected together to form a unitary base of the required number of lines.

The tap bases are each formed of an oblong piece 7 of porcelain or other suitable 100 insulation. These bases are provided with any desired number of channels 8 in their upper faces for the passage of the line wires 9, and with grooves or openings 10 for the reception of the metallic tap or connecting 105 strips 11. Each of the tap strips shown has perforations 12 in its ends and one or more portions 13 that rises into a wire channel, the remainder of the strap lying in the opening in the insulating base below the wire 110

channels. Each of the raised portions of these tap straps is provided with a screw fastened cap 14 by means of which a bared section of a line wire may be clamped to the strap. The tap base shown in Figs. 5 and 6 has a tap strap with a capped raised portion in an outside wire channel, which enables this block to be located between and connected with two branch units in such manner that the branch units may be electrically connected with one outside wire of the main line, when one of these blocks is turned one way, as shown at the top of Fig. 1, and when turned around it enables two branch units to be connected with the other outside wire of the main line, as shown at the bottom of Fig. 1. The capped portion of the tap strap of the base shown in Figs. 7 and 8 rises in the middle wire channel. This enables a branch unit or two branch units to be electrically connected with the middle wire of the main line, as shown at the center of Fig. 1. For connecting two opposite branch units with both outside wires the tap base may be provided with tap straps that rise in the path of the two outside wire channels of the base, as shown in Figs. 9 and 10.

The tap straps are cheaply formed and are easily inserted in the recesses in the readily obtained porcelain bases, and when the individual single line bases are joined together to form multiple line branch bases and the tap straps are fastened between them the assemblage forms a complete unitary service cut-out with the parts to be electrically connected with the line wires in convenient position and proper relation, and all of the other parts suitably insulated.

40 The invention claimed is:

1. An electric current carrying device comprising a plurality of individual single line cut-out bases of insulating material, each bearing two conducting circuit wire terminals, means for mechanically joining said single line cut-out bases, a plurality of individual single line tap bases of insulating material, each bearing a conducting tap-strap, each of which straps has means for mechanical and electrical connection with a circuit wire terminal of a cut-out base and for mechanical and electrical connection with a main line wire.

2. An electric current carrying device comprising a plurality of branch cut-out bases of insulating material bearing conducting circuit wire terminals, and a plurality of individual single line tap bases of insulating material bearing conducting tap-straps, said tap-straps having means for mechanical and electrical connection with circuit wire terminals of the branch bases and for mechanical and electrical connection with main line wires.

65 3. An electrical cut-out base of insulating

material having a plurality of pairs of conducting circuit wire terminals, and a plurality of single line tap bases of insulating material having conducting tap-straps provided with means for mechanical and electrical connection with said circuit wire terminals and with main line wires. 70

4. An electrical cut-out base of insulating material having a plurality of pairs of conducting circuit wire terminals, and a plurality of tap bases of insulating material, said tap bases having wire channels in their upper faces and recesses opening into said channels with conducting tap-straps located in said recess, said tap straps having means for connection with circuit wire terminals of the cut-out bases and means for connection with main line wires. 75 80

5. The combination of a cut-out base of insulating material bearing pairs of conducting circuit wire terminals, tap bases of insulating material having wire channels in their upper faces and recesses opening into said channels, and tap-straps located in said recesses and having portions extending into the wire channels, said straps at their ends having means for connection with circuit wire terminals of the cut-out base and in the wire channels having means for connection with line wires. 85 90 95

6. The combination of a cut-out base of insulating material bearing circuit wire terminals, and a tap base of insulating material having a wire channel in its upper face and a recess opening into said channel with a conducting tap-strap located in said recess and having a portion extending into the wire channel, said strap having means for connection with a circuit wire terminal and means for connection with a line wire. 100 105

7. A tap base formed of insulating material having a wire channel in its upper face and a strap recess opening into said channel, with a tap-strap located in said recess and extending into said channel, said strap having means at its end for connection with a branch line terminal and means in said channel for connection with a main line wire. 110 115

8. An electric current carrying device comprising a plurality of single wire tap units, means on each of the said single wire tap units for making electrical connection with a main line wire, a plurality of single wire branch line units, means for connecting the said branch line units together, means on each single wire branch unit adapted for electrical connection in a branch circuit, and means for electrically connecting each of the said single wire branch units with one of the said single wire tap units. 120 125

9. An electric current carrying device comprising a plurality of single wire tap units, a conductor and connecting member mounted on each of the said single wire tap units, a plurality of single wire line units, 130

terminals on each of the said single wire line units adapted for electrical connection in a branch circuit, means for connecting the said single wire line units together, and 5 means for connecting the said conductor member of each of the said single wire tap units to a terminal of one of the said single wire line units.

10. An electric current carrying device 10 comprising a plurality of single wire tap units, a current carrying and connecting member on each of the said single wire tap units, means for connecting a main line wire to each of the said current carrying and connecting members, a plurality of single wire line units, means for connecting the said single wire line units together, terminals on each of the said single wire line units adapted to receive a circuit opening device, and 15 means for connecting the said current carrying and connecting member of each of the said single wire tap units to one of the

terminals of one of the said single wire line units.

11. An electric current carrying device 25 comprising a plurality of single wire tap units, a conducting member on each of the said single wire tap units extending through and projecting beyond the opposite sides of the same, means for electrically connecting 30 a main line wire to each of the said conducting members, a plurality of single wire line units, means for connecting the said single wire line units together, and terminals mounted on each of the said single wire line 35 units and adapted to receive a circuit opening device, the said projecting ends of the said conducting members being adapted to be electrically connected to the terminals of the circuit opening devices mounted on the 40 said single wire line units and thus mechanically connect the units together.

JOSEPH SACHS.
